HIS ATTORNEY

UNITED STATES PATENT OFFICE.

JAMES MORRISON, OF TOLEDO, OHIO, ASSIGNOR TO THE OWENS BOTTLE COMPANY, OF TOLEDO, OHIO, A CORPORATION OF OHIO.

BOTTLE.

Application filed August 4, 1925. Serial No. 48,079.

My invention relates to improvements in bottles or other containers for liquids and, more particularly, to means for preventing drippings from running down the outside 5 surface of the container. In dispensing liquids from the usual forms of bottles or like containers, a certain amount of the contents or drippings will frequently run down the neck and sides of the container. This is 10 objectionable for various reasons, among which are gumming or massing up the bottle, staining and disfiguring the bottle, obliterating labels or printed directions, destroying or corroding the metal or other caps used as 15 closures for the bottles and staining or injuring the hands, particularly where acids are dispensed.

An object of my invention is to provide simple and practical means to overcome the 20 above and other objections by preventing such drippings from running down the sides of the container.

The invention is herein shown in connection with a "sprinkler" type of bottle having 25 a restricted outlet orifice for dispensing the contents of the container drop by drop, or in the form of a spray. Obviously, however, the invention may be adapted to various other forms of containers.

30 Other features of the invention will appear hereinafter.

In the accompanying drawings:

Figure 1 is a top plan view of a bottle constructed in accordance with my invention.

35 Figure 2 is a side elevation of the same.

Figure 3 is a fragmentary sectional elevation taken on Figure 1 at the plane of the line A—A.

Referring to the drawings, a bottle 3 is 40 provided with a bead 4 surrounding the neck and making a seat for the usual cap which is assembled over the screw threads 6. A peripheral groove 5 is formed in the upper face or top surface 7 and surrounds the outlet 45 opening 8. It will be noted that the upper face portion 7 is constituted of two parts, viz,—a central or insular portion bounded by the groove 5, and a ledge 9, of somewhat higher elevation than said central or insular 50 portion, the former serving as a pouring lip over which the contents run while issuing from the container.

It will be apparent that by having the aforesaid ledge 9 disposed around the circumference of the upper surface 7 and a groove 5,

in juxtaposition thereto, very effective means for the retention of drippings is provided, which otherwise would pass over the neck of the container. Further, the depression of the central or insular portion affords a path of 60 removal of an excessive amount of drippings that have accumulated. It will be seen that said drippings above the level of aforesaid insular portion, but below the level of ledge 9, will be returned to the container. Thus, very 65 effective means is presented to stop drippings from running down the sides of a container. By forming the peripheral groove 5 in the top surface of the bottle neck, the ledge 9 is spaced from the insular portion 7 so that 70 the latter serves as a pouring lip over which the contents pass when the container is inverted. Accordingly, the highest point of the ledge 9, seldom, if ever, contacts with the contents while the latter is being poured from 75 the container. Thus it is seen that drippings will not run down the sides of the container and such of the drippings as do not return to the interior of the container by gravity will be retained in the peripheral groove 5 and 80 enclosed by a cap (not shown) which may be threaded upon the container neck.

Modifications may be resorted to within the spirit and scope of my invention.

What I claim is:

1. A bottle comprising a neck portion having a transverse wall at its outer end, said wall formed with a restricted aperture and an annular groove concentric with the aperture in the outer face of the wall, the outer 90 wall of said groove being of higher elevation than the remaining portion surrounding the aperture.

2. A container, including a neck portion having a horizontally disposed upper face formed with a central aperture, a peripheral groove, and an outer ledge of slightly higher elevation than said upper face, for the purpose of the elimination of side drippings.

3. A container, including a neck portion having a horizontally disposed upper face, formed with an upwardly projecting ledge of higher elevation than the latter and disposed around the perimeter thereof as a barrier to the egress of drippings as said bottle is reverted in use to its normal upright position, said upper face also formed with a groove in juxtaposition with, and substantially the same contour as said ledge, said upper surface further formed with an outlet 110

aperture down which an overflow of drippings from said groove is disposed by gravity action, the edge of the aperture acting as a pouring lip.

- 5 4. A bottle comprising a neck portion having a restricted central aperture, the top surface of the neck portion comprising an intermediate annular surface portion surrounding said aperture, an annular groove surrounding said surface portion, and an annular ledge surrounding the groove and forming the periphery of said top surface, the in-

ner wall of said ledge forming the outer wall of said groove, said intermediate surface being at a slightly lower level than the top surface of said ledge, said ledge being so positioned relative to the central aperture that in the normal operation of pouring a liquid from the bottle, said liquid will not come in contact with said ledge. 15

Signed at Toledo, in the county of Lucas and State of Ohio, this 1st day of August, 1925.

JAMES MORRISON.
